UNITED STATES PATENT OFFICE

2,538,048

OPERATING SLIDE FOR FIREARMS

Wilbur A. Schaich, Highland Park, Mich.

Application November 10, 1948, Serial No. 59,325

3 Claims. (Cl. 89—129)

(Granted under the act of March 3, 1883, as
amended April 30, 1928; 370 O. G. 757)

1

The invention described herein may be manufactured and used by or for the Government for governmental purposes without payment of any royalty thereon.

This invention relates to an improvement in firearms, more particularly to improving the timed opening of an automatic firearm bolt.

In many firearms of the automatic or semi-automatic type the timing of the action is such that the breech closure member or bolt opens under relatively high residual breech pressure. Opening under such a condition adversely affects the firearm by producing excessive forces on the recoiling parts, harder extraction of the fired case due to its expanded condition and hence greater possibility of fracture of the extractor and the moving components of the action.

This condition is commonly found in the U. S. carbine, caliber .30, M1 wherein the gas utilized to actuate the operating slide of such firearm is tapped from the barrel at a point quite near the chamber hence where the breech pressure is exceedingly high. The tappet type actuation of the operating slide coupled with a short dwell travel of such slide before contacting the bolt lug cam results in the repeated unlocking of the bolt or breech member before the chamber pressure has dropped to the proper level for safe opening of the firearm bolt.

Various modifications have heretofore been utilized in order to delay the opening of the bolt of the above mentioned firearm. One of such modifications was to increase the dwell portion of the operating cam contained in the bolt handle of the inertia slide and another was to increase the weight of the inertia slide. Neither of these modifications satisfactorily accomplished the desired end. Increasing the weight of the operating slide, while slightly delaying the opening of the firearm bolt, added materially to the weight of the firearm. Increasing the dwell portion of the operating cam proved unsatisfactory and impractical due to design limitations required to maintain interchangeability.

Accordingly, it is an object of this invention to provide an improved firearm of the gas operated, automatic type characterized by the delayed unlocking of the bolt member to insure that the breech pressure has dropped to a safe level.

A further object of this invention is to provide means whereby the dwell period of an operating slide of a firearm may be readily increased without major redesign of such firearm to delay unlocking of the firearm bolt until a desirably low and safe breech pressure is reached.

2

A particular object of this invention is to provide an improved inertia slide for an automatic firearm of the type similar to the U. S. carbine, caliber .30, M1, whereby improved timing of the opening of the bolt is achieved.

The specific nature of the invention as well as other objects and advantages thereof will clearly appear from the following description of a preferred embodiment as shown in the accompanying drawings in which:

Fig. 1 is a fragmentary top elevational view of the receiver end of a firearm embodying this invention, showing the battery position of the improved inertia member and also the recoil position of such member in dotted outline.

Fig. 2 is a fragmentary side elevational view of the firearm of Fig. 1 shown with the stock removed to better illustrate the improved inertia slide.

Fig. 3 is a longitudinal sectional view taken along the line 3—3 of Fig. 2.

In Figs. 1 and 2 there is shown a firearm embodying this invention. While not limited thereto, this invention is shown as embodied in a gas operated, automatic firearm of the type known as the U. S. carbine, caliber .30, M1. Such a specific example is merely chosen for purposes of illustration, as obviously this invention can be applied to any gas operated firearm having a reciprocating operating slide or breech actuating member. The firearm shown in such figures comprises mainly a receiver 1, a barrel 2, an operating slide 3 and a stock 4 housing such members.

Barrel 2 is secured to receiver 1 and operating slide 3 is mounted on barrel 2 for longitudinal reciprocal movement in the usual manner. However, slide 3 is formed in two pieces, a substantially rectangular shank portion 14, and a handle portion 5.

Such handle portion 5 telescopes into a hollow bar-like member 6 projecting rearwardly from inertia portion 14 and integrally formed therewith, as will be presently described. A plunger 7 surrounded by a spring 15 is provided to bias slide 3 forwardly to battery position. The forward end of plunger 7 abuts the rear surface of portion 14 while the other end of spring biased plunger 7 is contained within a suitable recess provided in receiver 1. Handle portion 5 provides the usual operating connection to a bolt 8 slidably contained within receiver 1. A bolt lug (not shown) engages a suitable cam slot in the inside face of handle portion 5, likewise not shown.

Handle portion 5 is provided with a forwardly projecting integral bar-like end 10 which is

adapted to be slidably inserted within a longitudinal recess 9 provided in bar 6, such recess and bar preferably being non-circular, for example, of rectangular shape. A longitudinal slot 11 is provided in bar 10 and a transverse hole 12 is provided in bar 6 so as to permit insertion of a pin 13 through slot 11 and hole 12, thereby limiting the extent of slideable separation of handle portion 5 to bar 6 of slide 3.

Each end of pin 13 is preferably peened, as shown in Fig. 3, to permanently secure such pin in bar 6. When operating slide is in its battery position on the firearm, as shown in Figs. 1 and 2, the portion 14 is effectively separated from handle 5 by virtue of slot 11. The amount of such separation is here shown as limited to approximately one-half inch, although greater or lesser separation may be easily attained by lengthening or decreasing the length of slot 11. Spring biased plunger 7 maintains the two parts of the operating slide in such separated position until discharge of a cartridge as will be presently described.

When a cartridge is fired in the firearm, the actuating gases impinge on a gas actuating mechanism (not shown) which in turn imparts a rearward blow to slide 3, thereby driving such slide rapidly rearwardly. The portion 14 of slide 3 travels a substantial distance, bar portion 10 telescoping into recess 9 of bar 6 before the rear end of bar 6 effectively engages handle portion 5 by striking shoulder 10a.

Up to the time such impact occurs, no unlocking movement of the handle portion 5 of bolt 8 has taken place. In other words, the bolt 8 is securely locked to the receiver 1 during the initial rearward travel of inertia portion 14 of the slide. Obviously this introduces a substantial delay thereby providing more time for reduction of pressure in the barrel.

When the rear end of bar 6 strikes handle portion 5, such handle is moved rearwardly, thereby adding the usual time delay or dwell period incorporated in the unlocking cam (not shown) to that obtained by telescoping the inertia slide. At the termination of the secondary dwell movement of the handle portion 5, the locking lug of the bolt (not shown) is rotated by the cam slot (not shown) contained in the handle portion 5 to effect unlocking of such bolt from receiver 1. Due to the momentum of inertia slide 3 and to residual gas pressure in the chamber, bolt 8 is driven rearwardly to its recoil position as shown in dotted outline in Fig. 1.

From the foregoing description it is thus seen that an added time lag or dwell period is introduced prior to opening of the firearm bolt by means of the telescoping operating slide provided by this invention. The time lag between firing of the cartridge and unlocking of the bolt so introduced plus the normal dwell period of the unlocking cam of the operating slide provides ample time for lowering of the breech pressure to a level permitting safe opening of the bolt.

When the bolt is unlocked under relatively low chamber pressure the fired cartridge case is easily extracted and the recoil forces acting on the receiver and moving parts are greatly reduced.

5 It is further desired to point out that the means provided by this invention for achieving any additional time lag or dwell period to improve the timing of the opening of the firearm bolt, is achieved in a simple manner which is inexpensive 10 to manufacture and easy to produce, does not require modification of the major components of the firearm, and may be interchangeably applied to existing firearms merely by substitution of the operating slide. Furthermore, the telescoping two part operating slide does not impair the manual operation of the operating slide.

I claim:

1. In an automatic firearm with a reciprocable bolt and a gas operating mechanism, an operating 20 slide having two parts, a first part serving as an inertia device and engaging the gas operating mechanism and a second part engaging the bolt; and time delay means connecting the two parts, said time delay means comprising a rod-like extension on one part carrying an inclosed rectangular slot, a pin rigidly secured to the other part engaging the slot, and recessed means in the said other part slideably receiving the rod-like extension and thereby permitting limited telescopic motion of the operating slide when the inertia part is actuated.

2. A two part operating slide for a gas operated firearm with a reciprocable bolt comprising a forward shank part serving as an inertia device, a rearward handle part, and time delay means connecting the forward and rearward parts and preventing premature action of the handle part, said time delay means comprising a rod-like extension on the handle part carrying an inclosed rectangular slot, a pin rigidly secured to the shank part engaging the slot, and a bore in the shank part slideably receiving the rod-like extension and thereby permitting limited telescopic motion of the operating slide when the inertia part is actuated.

3. An operating slide as in claim 2 in which the pin of the time delay means extends transversely through the rectangular slot and travels longitudinally therein.
